United States Patent Office.

W. G. RAOUL, OF INDEPENDENCE, LOUISIANA.

Letters Patent No. 99,351, dated February 1, 1870.

IMPROVEMENT IN FARE-BOXES FOR RAILROAD-CARS.

The Schedule referred to in these Letters Patent and making part of the same.

To all whom it may concern:

Be it known that I, W. G. RAOUL, of Independence, in the parish of Tangipahoa, and State of Louisiana, have invented a new and useful Improvement in Car-Fare Boxes; and I do hereby declare that the following is a full, clear, and exact description thereof, which will enable others skilled in the art to make and use the same, reference being had to the accompanying drawings, forming part of this specification.

This invention relates to a new and useful improvement in boxes for receiving passengers' fare on cars of street-railroads, omnibusses, and other vehicles for transporting passengers; and consists in the construction and arrangement hereinafter described.

In the accompanying drawings—

Figure 1 is a vertical section of the fare-box, through the line $z z$ of fig. 2.

Figure 2 is a front elevation.

Figure 3 is an end elevation.

Similar letters of reference indicate corresponding parts.

This fare-box consists, mainly, of an outer fixed glass or transparent cylinder, a , and an inner revolving transparent cylinder, b , supported by the ends of the box c , which extend up for that purpose.

The inner cylinder is confined to a central shaft, d , by means of heads on the shaft.

The ends of the shaft pass through the projecting end-pieces e of the box, and have gear-wheels, f , fastened thereto, as seen in the drawing.

The inner cylinder is revolved by means of levers g g , on each end of the box, each of which has a segment of a wheel, h , attached to their inner sides, the cogs of which engage with the wheels f , when the levers are moved back and forth. These levers are pivoted to the ends of the box c , at i , and are connected together, above the cylinders, by the head-piece j .

k k represent stop-pins, which limit the movement of the levers.

Each of the glass cylinders a b has two apertures, m m' and n n' .

By pushing the head-piece j , as indicated by the arrow, the aperture m' , in the cylinder b , will be turned up, so as to register with n' in the cylinder a .

When the fare is introduced, the levers are thrown back, as seen in fig. 1, by means of springs o .

On the inside of the revolving cylinder b are two aprons, p q .

When the fare is introduced, it slides from p on to q , and from thence on to the bottom of cylinder b , as the reverse motion takes place, where it is retained, for inspection by the driver and passengers, until the levers are worked again, when the fare slides from the cylinder, and is deposited in the cash-drawer beneath.

Light is thrown through the transparent cylinders in the night-time (by means of reflectors) from the ordinary car-lamp, by which means the interior of the cylinders is illuminated.

In the lower portion of the fare-box, beneath the cash-drawer, the lower ends of the levers g are connected together by the bar r , to which a spring bell-crank, s , is attached, supported by the stand t .

u is a bell.

Whenever the levers are operated, as for the introduction of fare, the bell-hammer v is raised, and, when the levers are thrown back by the springs o , the hammer strikes the bell, giving notice that a fare has been deposited.

w represents the cash-drawer.

The principal object of this invention is to avoid the necessity of employing a conductor on street-cars for receiving the passenger-fare. By this arrangement, the passenger deposits his own fare. To do this, he pushes back the levers, by means of the head-piece j . When the apertures m m' register, (which takes place when the levers strike the stops k), he deposits his fare, which is received, and held for inspection by the driver, as well as by the passengers, until another fare is deposited, as before stated.

Having thus described my invention,

I claim as new, and desire to secure by Letters Patent—

1. The combination of the transparent cylinders a b , having apertures m m' , n n' , and aprons p q , with gears f f , rack h , levers g g , spring o , and pins k k , all arranged as set forth.

2. In combination with subject-matter of above clause, the cash-drawer and the striking-device s v u , all as shown and described.
